CORNICE

William J. Purcell, Chattanooga, Tenn., and George R. Murdock, New York, N. Y., assignors to H. L. Judd Company, Inc., Wallingford, Conn., a corporation of Delaware

Application July 1, 1942, Serial No. 449,218

9 Claims. (Cl. 160—38)

Our invention relates to a cornice which may, for example, be used on a window frame, and more particularly to cornice construction whereby a cornice with finished corners may easily be produced.

It has been common practice to make the corners of cornices by mitering at a 45 degree angle the ends of the main or front part of the cornice and also the front ends of the return or bracket parts, so that the mitered ends when placed together will form a 90 degree corner. The mitering of the ends to be joined at right angles is frequently not accurate and the resulting joint is poor; for example, the joint may not be well closed. In other instances prefinished corners are used. However, with the last mentioned arrangement the front parts attached to the two corners must be connected by a more or less unsightly extender which not only connects the ends but permits adjustment in length of the cornice.

It is the principal object of our invention to provide a cornice or cornice construction whereby it will be relatively easy for one to construct a finished cornice by cutting off a suitable length of cornice board and attaching to the same at opposite ends, returns or bracket portions of the cornice board, by means of suitable finished corners.

Other objects of the invention will be hereinafter pointed out or will become apparent to those skilled in the art.

In the drawing which shows, for illustrative purposes only, a preferred form of the invention—

Fig. 1 is a perspective view, showing the upper part of a window frame and attached thereto a cornice, illustrating one embodiment of the invention;

Fig. 2 is a top plan view of the left end of the cornice in Fig. 1;

Fig. 3 is a section on the line 3—3 of Fig. 2;

Fig. 4 is a section on the line 4—4 of Fig. 1;

Fig. 5 is a perspective view illustrating the interior of one form of finished corner; and

Fig. 6 is a perspective view illustrating the interior of a device for attaching the cornice to the window frame.

The invention will be described as embodied in a window cornice of which the front or rail 10 is a single piece of cornice board and the returns or bracket portions 11 are pieces of the same material as the single longitudinal piece or rail. Hitherto, the ends of the rails and the forward ends of the returns or brackets have

generally been joined by means of miter joints which involve considerable skill and care in making, and as a matter of fact joints made in this way usually have noticeable gaps, particularly if made at the places where the cornices are to be used. It will be evident that the returns or brackets may be made from waste pieces of cornice boards.

The parts so far referred to are well known to those skilled in the art. According to our present invention, the front rail 10 and the returns 11 are connected together by preformed finished corners 12 which may take different forms.

Each of these corners 12 may comprise two parts or sides 13 of cornice board accurately mitered as by a machine, secured firmly together by suitable means which may include reinforcing metal plates 14 placed at the tops and also the bottoms of said parts and secured firmly thereto, as by screws 15, to retain said parts in fixed relation with respect to each other. It will be evident that the corners 12 may be made of relatively short pieces of cornice board with the outer ends of the sides 13 finished with curved surfaces conforming in contour to the rails and to the returns.

In order for the corners 12 to fit closely over the ends of the rail and the returns, the inner faces of the sides 13 must be formed with such contours (Fig. 3) as will complement the contour of the front face of the rail, thereby enabling the corners 12 to fit closely over adjacent ends of the rail 10 and returns 11, as illustrated in Fig. 3.

As illustrated in Figs. 2 and 4, the rail 10 is cut with square ends and to the length required by the width of the window frame and the thickness of the returns 11, and the corners 12 are placed thereon so that the ends of the rail 10 abut against the corresponding sides of the corners. Then the forward ends of the returns 11 are inserted in the cornice corners 12 with their ends abutting against the inner sides of the ends of the rail 10. The parts thus assembled may be secured in position by screws 16 passing through suitable openings in the plates 14 and screwed into the members 10 and 11.

Although the illustrated embodiment of the invention shows screws 16 securing the plates 14 to the rail 10, these screws might be omitted, leaving the ends of the rail secured in the corners between the abutting ends of the returns 11 and the corresponding sides of the corners. Obviously the arrangement might be changed so that the outer ends of the returns 11 would

abut against the inner faces of the outer sides of the corners 12 and would be engaged at their inner faces by the ends of the rail 10.

The completed cornice may be supported on the window frame by suitable means such as angular brackets 17 (Fig. 6), one plane portion 18 of each bracket 17 having horizontal slots 19 and being secured to the inner end of the corresponding return by screws 20 passing through said slots 19, and the other or flange portion 21 of each bracket being secured to a side of the window frame by screws 22 passing through a keyhole slot 23 and a lower opening 24 in such flange portion. The screws for the keyhole slots may be installed in advance and the cornice hung thereon with the upper screws 22 engaging the upper ends of the keyhole slots 23. The cornice may further be secured in place by other screws 22 passing through the lower openings. All of the screws 22 may be tightened and the cornice strongly secured in fixed position.

The present invention involves many advantageous features relating to the parts of the cornice and assembly thereof. The return members or brackets 11 may be made up in advance, whereby the only preliminary step to be performed on the job is to cut off a suitable length of rail. Then the parts may be assembled to produce the final form shown in the drawing. The corners are prefinished and conform to the contour of the board or the forward rail. The parts are held together with a minimum of connections. There is no unsightly extender for the rail, such as required in cornice constructions where there are rail sections extending inwardly from preformed corners and the adjacent ends have to be held together by extenders which connect the adjacent ends of the rail sections and hold these sections in alignment. Furthermore, the dealer or consumer can make and install this particular cornice without millwork or special tools.

While the invention has been described in considerable detail and a preferred form illustrated, it is to be understood that many changes and modifications may be made within the scope of the invention as defined in the appended claims.

What we claim is:

1. A cornice of the character described comprising a front rail of cornice strip material, returns, and means for connecting the returns to the ends of said rail including premade cornice corners into each of which fits the forward end of a return and the adjacent end of said rail.

2. A cornice comprising a rail of the requisite length of cornice board, returns formed from the same cornice board, and means for connecting

the returns to the rail including premade corners each with two sides and reinforcing means connecting said sides at the top, each of said corners receiving beneath said reinforcing means the front end of a return and the adjacent end of said rail.

3. A cornice comprising a rail of cornice board cut to length, returns formed from said cornice board, and premade corners receiving the ends of said rails and the corresponding ends of said returns, each corner having two sides with the same exterior contour as said cornice board and the contour extending across the ends of said sides to merge in appearance with the front surface of the rail.

4. A cornice comprising a rail of cornice board, returns of such cornice board, and premade corners comprising sides and reinforcing plates connecting said sides at top and bottom, and receiving the forward ends of the returns and the adjacent ends of the rail, the forward ends of said returns being secured to said plates.

5. A cornice comprising a rail of cornice board, returns of such cornice board, and premade corners each having sides outside of the rail and returns, the outer surfaces of said sides having the same contour as said cornice rail and the inner surfaces of said sides having contours substantially complementary to the contour of the outer face of the cornice board to facilitate a close fit with the outer surfaces of the ends of the rail and the returns.

6. A premade cornice corner for connecting the rail and returns of the cornice, comprising two sides having the same exterior contour as the said rail and returns, and reinforcing plates connecting the sides at the top and the bottom close to the edge of said corner.

7. A premade cornice corner for connecting the rail and returns of the cornice, comprising two sides having the same exterior contour as the rail and the returns, and an interior contour complementary to the exterior contour of said rail and returns.

8. A premade cornice corner for connecting the rail and returns of the cornice, comprising two side pieces secured together, each of said side pieces having inside contours complementary in shape to the outside contours of the rail and returns of the cornice.

9. A premade cornice corner for connecting the rail and returns of the cornice, comprising two side pieces secured together, said side pieces having surface contours complementary in shape to the adjacent surface contours of the rail and returns to interfit therewith.
